MATCH PACKAGE

Henry B. Watkins, Worthington, Ohio, assignor to
The Kilgore Manufacturing Company, Tipp
City, Ohio, a corporation of Ohio

Application August 11, 1942, Serial No. 454,479

8 Claims. (Cl. 206—29)

1

This invention relates to matches and more particularly to a match package in which the matches are adapted to be ignited as they are withdrawn from the package.

It is a principal object of the invention to provide a match package having positive safety features in that ignition of the match is not accomplished by mere withdrawal thereof from the package, but only when ignition is definitely intended and the act of withdrawal is accompanied by the application of pressure to a predetermined area of the package.

It is a further object to provide such a package in which the ignition of the match occurs only after it has left the match holding pocket and under such conditions that adequate space is available for the venting of the flame and gases without burning the package itself or the hand of the user.

It is a still further object to provide a match package of this character in which the matches can be safely replaced in the package for subsequent use in the event of a failure of ignition when the match is first withdrawn, thus assuring maximum use of all matches in the package.

In the drawing,

Fig. 1 is a plan view of a match package constructed in accordance with the present invention with the cover opened out and folded flat in order to more clearly illustrate the construction thereof;

Fig. 2 is a perspective view of the package showing the way in which it is held for use, certain of the parts being broken to illustrate the construction more clearly;

Fig. 3 is a sectional view through the package on the line 3—3 of Fig. 2;

Fig. 4 is a plan view of a modified form of package, the cover being opened out in the same manner as shown in Fig. 1;

Fig. 5 is a sectional view through the modified form of package shown in Fig. 4;

Fig. 6 is a plan view of a package having a double match strip arrangement, the package being folded flat to show the construction thereof; and

Fig. 7 is a sectional view through the form of package shown in Fig. 6.

In the construction of match packages containing matches which are adapted to be ignited upon withdrawal, the match heads are held within pockets with the ends projecting outwardly therefrom, and upon withdrawal of a match from its pocket, ignition takes place through the provision of a striker strip or frictional surface which

2

is located within the match retaining pocket. The match head is usually yieldably confined within the pocket, requiring the exercise of a definite pull in order to effect withdrawal thereof from the pocket, and it is during the course of its travel through the pocket and while the head is still confined by the pocket and caused thereby to frictionally engage the striker strip, that ignition takes place. As a result, the flash of ignition and initial burning take place with the head still confined in the quite narrow limits of the pocket, this space affording only an inadequate vent for the escape of the flame and the combustion gases resulting therefrom. If the match is withdrawn from the pocket relatively slowly, or in the event that the match should actually be caused to ignite and the head allowed to remain within the match pocket, the pocket, and through it, the hand of the user, may be subjected to the action of the flame and heated gases for a sufficient period of time to be burned or injured.

In accordance with the present invention, a positive safety feature is provided in that the mere act of withdrawing the match from the package does not provide for ignition thereof, but a further and definite application of pressure is required to be made upon a predetermined area of the package, when it is desired to have ignition take place. Thus there is required a definite and correlated action comprising the withdrawal which is effected by one hand, and the application of pressure in a definite area which is effected by the other hand of the user, such coordination providing for the positive ignition of the match as opposed to accidental ignition thereof.

Further, the invention provides for the ignition of the match taking place only after the head thereof has been withdrawn or removed from the confining pocket. Thus the flash of ignition and preliminary combustion takes place in an area which is relatively free in comparison with the confined space of the pocket and which is furthermore located remotely with respect to the heads of the other matches remaining in the pockets so that there is little or no possibility of accidental ignition thereof. This is accomplished through the location of the striker strip in the area outwardly of and beyond the outer ends of the match pockets so that the match heads do not frictionally contact the striker strip until they have been substantially withdrawn from the pockets. A flexible cover member is provided which overlies the striker strip and which may be depressed upon manual application

of pressure to the cover in a predetermined area to thereby force the match head, in the course of its withdrawal and after its release from the pocket, to travel across the striker strip in friction and igniting contact therewith. A relatively light pressure is sufficient for this purpose, the pull required to be exerted on the match head during its passage across the striker strip being substantially less than that to effect its withdrawal from the pocket. Thus it is drawn positively and rapidly across and in frictional contact with the striker strip, assuring its ignition and continued withdrawal and final separation from the package.

Referring to the drawing in which preferred embodiments of the invention are shown, the form shown in Figs. 1 to 3 comprises a main cover 10 which is preferably a strip of relatively heavy paper or paperboard having an intermediate fold line 11 located eccentrically such as to provide a back cover portion 12 and a front cover portion 13. The match holding strip is shown at 15 comprising a broad flat strip of paper material 16 and an overlying narrower strip of paper material 17 which is corrugated and which when assembled and secured to the strip 16, provides a series of spaced elongated match holding pockets 18 leaving the upper part of strip 16 exposed. The depth of the corrugations is slightly less than the thickness of the match heads so that the heads are confined and yieldably held in place therein. Preferably the ends of the pockets adjacent the fold line 11 are crimped and flattened as shown at 19 in order to close the inner ends of the pockets. The strips are conveniently secured to each other and strip 16 is secured to cover portion 12 by means of adhesive.

The matches 20 are shown as provided with heads 21 carrying an ignitable compound and each received within one of the pockets 18. The matches have outer extending ends 22 which are somewhat wider than the body of the match to provide for grasping, the ends extending upwardly toward the upper edge of the cover portion 12 to be protected thereby while being available for withdrawal.

The pockets 18 are not formed with an extended friction surface and the matches may thus be inserted or withdrawn therefrom, the heads moving across the relatively smooth surfaces of strips 16 and 17 without sufficient friction to cause ignition. In order to provide for ignition, a striker strip of suitable frictional material is provided which is preferably formed as a coating of frictional material 25 upon the outer exposed part of the match package strip 16. In this position it occupies an area primarily located outwardly of the match pockets; as shown in Fig. 1 it may extend slightly below the outer edge of corrugated strip 17 in order to extend the area over which the manually applied pressure is effective to cause ignition while still causing ignition to occur essentially in the unconfined space beyond the pocket.

The match strip with the matches received in the pockets is assembled upon the back cover portion 12 in substantially the manner as shown in Fig. 1 and secured thereto by suitable means such as the application of adhesive. Thereafter the front cover portion 13 is folded over upon the match strip and secured to the top face of the corrugations, also preferably through the use of a suitable adhesive. By reference to Figs. 2 and 3 it will be seen that the cover portion 13 does not extend upwardly as far as the rear portion 12, but

that it overlies the match pockets 18 and projects upwardly only a limited distance beyond the top edge of the striker strip 25. This provides an overhanging part 28 or strip which extends along the top edge of front cover portion 13, this strip 28 being relatively flexible and forming a pressure applying area through which manual pressure can be applied in the direction of the striker strip. Preferably the area 28 carries suitable legends or instructions as shown in Fig. 2 identifying the area of the cover portion upon which pressure is to be applied by the user when ignition of the match being withdrawn is desired. The lower portion of the cover 13 is left clear and is adapted to receive advertising or other printed matter thereon.

Fig. 2 also illustrates the manner in which the package is held during the withdrawal of the match. Thus with the package held between the thumb and the forefinger of the left hand, the match to be withdrawn is grasped by the thumb and forefinger of the right hand. With the thumb of the left hand in position over the portion 28 of the cover, and substantially in line with the arrows showing the proper point of pressure application, a slight pressure upon strip 28 will cause it to be flexed and depressed toward the back cover portion 12 such as to confine the match head during the course of its withdrawal and to force it to move in friction and igniting contact across striker strip 25. It is found that a relatively slight pressure will suffice for producing the desired ignition, the pressure so applied actually being less than that which is applied to the end of the match in order to withdraw it from its pocket. When however the package is held in such a way that no pressure is applied to pressure strip 28, then the match may be withdrawn without igniting and if desired may be similarly replaced in its pocket. It will also be seen that upon ignition the flame and combustion gases are not confined to a small space but can escape laterally in all directions and thus the possibility of injury or damage to the user or to the package is substantially reduced or eliminated.

Referring now to Figs. 4 and 5, similar parts are shown with the same reference numbers and the description thereof need not be repeated. This construction differs in that the front cover portion 13 is made somewhat longer and is formed with a score line or depression 30 which separates pressure strip 28 from the main part of the front cover, the score line forming an inner rib which as shown in Fig. 5 projects toward and is located approximately in alignment with the outer edge of striker strip 25.

The operation of this construction is as follows: Rib 30 tends to concentrate the pressure applied by the thumb in a definite line above and substantially at the outer end of the striker strip so that as the head of the match is withdrawn under the rib, it is caused to come in frictional and igniting contact with the striker strip. Thus the applied pressure is made effective in the area desired even though the thumb should not be positioned accurately above the striker strip and in line with the head of the match being withdrawn. It will also be noted that in this arrangement the pressure strip 28 extends upwardly somewhat beyond the outer edge of the striker strip thus affording further protection to the hand of the user and tending to prevent any possible burning thereof.

In the arrangement shown in Figs. 6 and 7, the

cover is constructed substantially the same as shown in Figs. 4 and 5, except that in this form each of the inner faces of the cover receives a match strip 15, the two match strips being secured respectively to the inner faces of the covers with corresponding inner ends located adjacent the fold line 11. Preferably the strip carried by the back cover is spaced slightly farther from the fold line than that carried by the front cover. It will thus be clear that upon the folding of the cover portions upon each other, the two match strips may be secured in face to face contact by the application of adhesive providing a match package in the form shown in Fig. 7. In this arrangement the rear strip of matches projects up above the front strip so that they can be easily grasped and withdrawn first. As described above, the withdrawal of a match from either strip in the absence of pressure application to the pressure strip 28 may take place without ignition. However when ignition is desired, pressure is applied to the strip 28 thereby deflecting the flexible pressure strip and the rib 30 toward the back cover section 12, both front and back being flexed sufficiently to confine the match heads so that a match from either strip will be caused to frictionally engage the striker strip with which it is associated, in the course of its withdrawing action.

The invention therefore provides in a highly simple and satisfactory manner, a safety feature which is incorporated in the match package, avoiding accidental ignition upon mere withdrawal, and providing for ignition positively and freely when the act of withdrawal is performed in conjunction with the application of pressure to a predetermined area of the package.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A match package comprising a backing strip, a corrugated strip forming a series of pockets on said backing strip, matches having heads extending into said pockets and having ends projecting outwardly therefrom in position to be grasped and withdrawn while being protected by said backing strip, a striker strip on said backing strip located beyond the outer end of said pockets and engageable by the matches only after withdrawal thereof from the pockets, and a flexible cover separate from and overlying said pockets and extending outwardly a limited distance beyond the outer edge of said striker strip but terminating short of the outer ends of the matches and adapted to be manually pressed toward said striker strip to effect friction and igniting contact of said match head therewith as it is withdrawn while affording protection for the fingers of the user.

2. A match package comprising a match holding strip having a plurality of pockets formed therein, a backing strip to which said pockets are secured, matches having their heads received within said pockets and extending outwardly toward but not beyond the outer edge thereof in position to be withdrawn therefrom, a single striker strip carried on said backing strip and located at the withdrawal end and outwardly of said pockets and engageable with said match heads only after substantially complete with-

drawal thereof from said pockets, said backing strip being formed with an integral folded cover portion extending outwardly beyond said pockets and said striker strip and terminating inwardly of the ends of the matches and adapted to be pressed toward said striker strip to force the match heads into friction contact with said striker strip as the match is withdrawn and after it leaves said pocket while providing for insertion and removal of matches from said pockets without ignition in the absence of such pressure.

3. A match package comprising a match holding strip having a plurality of pockets formed therein, matches having heads extending into said pockets and having ends projecting outwardly therefrom in position to be grasped and withdrawn, a striker strip located outwardly of said pockets and engageable with the match head only after substantially complete withdrawal thereof from its pocket, and a flexible cover member secured over said pockets and having a free outer end overlying and projecting beyond said striker strip in the direction of withdrawal of the matches, said striker strip and said outer end of said cover member being in substantially free and yielding relation to each other providing for removal and replacement of the matches therebetween without ignition, said outer end being adapted to be manually pressed toward said striker strip to force said match heads during withdrawal into friction and igniting contact with said striker strip following their removal from the pockets.

4. A match package comprising a match holding strip having a plurality of pockets formed therein, matches having heads extending into said pockets and having ends projecting outwardly therefrom in position to be grasped and withdrawn, a striker strip located at the outer end of said pockets and engageable with the match head only after withdrawal thereof from its pocket, and a flexible cover member overlying said striker strip, said cover member having a transversely extending rib projecting toward said striker strip and adapted to be manually depressed to confine the match heads into friction and igniting contact therewith upon withdrawal.

5. A match package comprising a match holding strip having a plurality of pockets formed therein, matches having heads extending into said pockets and having ends projecting outwardly therefrom in position to be grasped and withdrawn, a striker strip located at the outer end of said pockets and engageable with the match head only after withdrawal thereof from its pocket, and a flexible cover member, said cover member having a transversely extending rib projecting toward said striker strip and substantially in alignment with the outer end thereof, said cover member and said rib being adapted to be manually depressed toward said striker strip to force said match heads into friction and igniting contact with said striker strip upon withdrawal.

6. A match package comprising an outer cover folded upon itself along an intermediate fold line providing a back cover portion and a front cover portion, a match holding strip having a plurality of pockets formed therein and secured to the inner face of said back cover strip, matches having heads extending into said pockets and having ends projecting outwardly therefrom in position to be protected by said back cover strip while being available for withdrawal, a striker

strip located beyond the outer end of said pockets and engageable by the match being withdrawn only after the withdrawal of the head thereof from its pocket, said front cover member being secured to said pockets and having a flexible portion adjacent its outer end extending outwardly beyond said striker strip and adapted to be manually pressed toward said striker strip to confine the match heads and force their frictional engagement therewith during withdrawal, said flexible portion and said striker strip being in substantially free and yielding relation to each other in the absence of said pressure and providing for removal and insertion of said matches without ignition.

7. A match package comprising an outer cover folded upon itself along an intermediate fold line providing back and front cover portions, match holding strips having a series of pockets formed therein secured to opposed faces of each of said cover portions, matches having heads extending into said pockets and having ends projecting outwardly therefrom in position to be grasped and withdrawn, a striker strip located beyond the outer end of each series of pockets and engageable by the match being withdrawn only after substantially complete withdrawal thereof from its pocket, said striker strips in the folded position of said cover being in spaced face to face relation with each other such that the matches may be withdrawn from the pockets without ignition, said front cover member having an outer flexible portion overlying and extending beyond said opposed striker strips and adapted to be manually pressed toward the back cover

portion to confine the space therebetween and force the match being withdrawn into friction and igniting contact with one of said striker strips.

5 8. A match package containing matches adapted to be ignited upon removal from the package under pressure comprising two strips of paper material secured together one of which is corrugated to provide a series of match holding pockets, the other of said strips being folded along a line substantially parallel to said corrugated strip forming two unequal parts folded one upon the other, matches having ignitable heads withdrawably confined in said pockets and extending beyond the shorter but terminating inwardly of the longer of said parts, a striker strip carried by the longer of said parts and located outwardly of said pockets and frictionally engageable with said match heads only after substantially complete withdrawal thereof from said pockets, the shorter of said parts forming a cover member secured in overlying relation upon said corrugated strip and having its outer end freely supported in overlying relation with respect to said striker strip and extending outwardly beyond said striker strip and terminating inwardly of the ends of the matches, the outer end of said cover member being freely supported and compressible upon application of pressure to the area thereof 20 directly above said striker strip and in line with the match being withdrawn to cause each said match to ignite under the combined action of being withdrawn and of said predetermined pressure application.
